INVENTOR

Waldemar Kops

BY

H. C. Kliesen

ATTORNEY

UNITED STATES PATENT OFFICE

90,810

DESIGN FOR A TOY BALLOON

Waldemar Kops, New York, N. Y., assignor to Kops Brothers, Inc., New York, N. Y., a corporation of New York

Application July 17, 1933. Serial No. 48,745

Term of patent 14 years

To all whom it may concern:

Be it known that I, WALDEMAR KOPS, a citizen of the United States, residing at New York, in the county and State of New York, have invented a new, original, and ornamental Design for a Toy Balloon, of which the following is a specification, reference being had to the accompanying drawing, forming a part hereof.

What I claim is:

The ornamental design for a toy balloon, as shown.

WALDEMAR KOPS.
